Specification for Design.

Patented Aug. 29, 1916.

Application filed May 19, 1916. Serial No. 98,701. Term of patent 3½ years.

To all whom it may concern:

Be it known that I, FRANK H. WAGGONER, a citizen of the United States, residing in Chicago, in the county of Cook and State of Illinois, have invented a new, original, and ornamental Design for Fans, of which the following is a specification, reference being had to the accompanying drawing, forming part thereof.

The figure shows one side of the fan which is preferably made of a piece of cardboard cut to the contour shown with the representation of a folding fan printed thereon.

I claim:

The ornamental design for a fan substantially as shown and described.

FRANK H. WAGGONER.
